UNITED STATES PATENT OFFICE.

JOHN LAXTON, OF TORONTO, ONTARIO, CANADA.

GAS-STOVE.

SPECIFICATION forming part of Letters Patent No. 390,377, dated October 2, 1888.

Application filed October 20, 1887. Serial No. 252,910. (No model.) Patented in Canada June 3, 1887, No. 26,837.

To all whom it may concern:

Be it known that I, JOHN LAXTON, of the city of Toronto, in the county of York, in the Province of Ontario, Canada, have invented 5 certain new and useful Improvements in Gas-Stoves, (for which I have obtained a patent in Canada, No. 26,837, dated June 3, 1887,) of which the following is a specification.

The object of the invention is to design a 10 stove in which the heat from the gas-jets shall be utilized to the fullest extent; and it consists in the peculiar combinations and the novel construction, arrangement, and adaptation of parts, the whole being constructed substantially as hereinafter more particularly explained.

Figure 1 is a vertical section through *a b* of Fig. 2, with parts of the inner plate, *O*, broken away. Fig. 2 is a vertical section through *c d* 20 of Fig. 1. Fig. 3 is a sectional plan through *e f* of Fig. 1.

A represents the upper oven, and *B* the lower oven. These ovens are separated by the cast-metal plate *C*, on the bottom of which is fixed the corrugated deflecting-plate *D*. The sides of the ovens *A* *B* are made of light sheet metal, and are surrounded on their three sides by a jacket, *E*, made of light sheet metal, and between which and the sides of the ovens 30 *A* and *B* an air-space, *L*, is left, as indicated. A cast-metal base, *F*, is provided, and a top, *G*, of similar material.

As I claim nothing peculiar in the pot-holes or manner of heating them, they do not appear 35 in the drawings.

Perforated pipes *H* are located in the bottom of the oven *B*, and a perforated pipe, *I*, is located near the top of the oven *B*, immediately below the deflecting-plate *D*. These 40 pipes *H* and *I* are suitably connected to the gas-main, and are provided with such cocks as may be necessary to properly regulate the supply of gas to be admitted into them. On either side of the oven *A*, I form, within the 45 jacket *E*, passage-ways *J*, leading from the top of the oven *B* to a point near the top of the oven *A*. The heat created by the burning gas which escapes through the perforations in the pipes *H* and *I* is conveyed through the pas-

sage-ways *J* into the chamber *J'*, from which it finally escapes through the pipe *K*. By this arrangement the heat from the burning gas is fully utilized.

Within the space *L* at the rear of the stove I arrange a coil of water-pipes, *M*, through which water is caused to circulate in the usual manner. At the bottom of the space *L*, I place a perforated pipe, *N*, which is supplied with gas in the same manner as the pipes *H* and *I*. When the gas escaping from the pipe *N* is lighted; the heat within the space *L* is very intense. Consequently the water passing through the pipes *M* is soon heated.

In practice I do not find that it is necessary to keep the gas from the pipe *N* constantly lighted, as the heat which radiates from the sides of the ovens *A* and *B* is sufficient to keep the water in the pipes *M* moderately hot. In order that the air in the space surrounding the ovens *A* and *B* may be kept 70 in circulation, I perforate the sides of the passage-ways *J*, and in order to increase the radiating-surface in the space *L*, I place on either side of the pipes *M* the corrugated deflecting-plates *O*.

What I claim as my invention is—

1. The combination, with the oven *A*, of the oven *B*, the plate *C*, separating said ovens and preventing communication therebetween, the perforated gas-pipe in the oven *B* in proximity to said plate, and the passage-ways *J*, connecting the top of the oven *B* with the top of the oven *A*, the jacket *E*, and the gas-jet arranged in the space between said jacket and the oven *B*, and the coil *M* above said gas-jet, substantially as described.

2. The ovens *A* and *B*, connected together by the passage-ways *J*, in combination with the plate *C*, separating said ovens, the perforated gas-pipe below said plate, and the deflecting-plate *D*, located at the top of the oven *B* in proximity to said perforated gas-pipe, substantially as and for the purpose specified.

3. The ovens *A* *B* and the plates *C* separating them, combined with the passage-ways *J*, connecting said ovens, the perforated pipes *H*, arranged around the bottom of the oven *B*, and the perforated pipe *I*, arranged near the top

of said oven, and both connected with a suitable source of supply, substantially as and for the purpose specified.

4. The combination, with the ovens A B, connected together by the passage-ways J, and the plate C, separating said ovens, of the perforated gas-pipe I in said oven B beneath the said plate, and the corrugated deflecting-plate

D, attached to the bottom of said plate C above the pipe I, substantially as described. to
Toronto, July 19, 1887.

JOHN LAXTON.

In presence of—

CHARLES C. BALDWIN,
J. M. JACKSON.
